UNITED STATES PATENT OFFICE.

PEDER CHRISTIAN SCHAAANNING, OF VESTRE AKER, NEAR CHRISTIANIA, NORWAY.

MAGAZINE GRINDING APPARATUS FOR THE MANUFACTURE OF WOOD-PULP.

1,341,156.

Specification of Letters Patent.

Patented May 25, 1920.

Application filed March 27, 1920. Serial No. 369,324.

To all whom it may concern:
Be it known that I, PEDER CHRISTIAN SCHAAANNING, a subject of the King of Norway, residing at Vestre Aker, near Christiania, Norway, have invented certain new and useful Improvements in Magazine Grinding Apparatus for the Manufacture of Wood-Pulp; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

It is a well-known fact that the greatest difficulty in obtaining a fully automatic operation of magazine grinding apparatuses for the manufacture of wood pulp depends upon the peculiar tendency of the wooden blocks to establish self-carrying bridge arches, so that the blocks during the refilling of the grinding compartment do not fall down automatically. Even if the magazine widens downwardly the blocks are able to form bridge arches which must be disturbed by hand power. These arches may be formed between the side walls of the magazine and from the pressing plate of the pressing member to the opposite side wall of the magazine or to the sharpening device casing, and the arches thereby decrease periodically the effective grinding pressure.

The present invention has for its purpose to remove these inconveniences.

This is obtained by arranging in the inner wall of the grinding compartment or its supply hopper one or more upwardly moving members which constantly carry upward some of the wooden blocks located nearest to the wall and some of which constitute in case an end block of a bridge arch, so that such arches are incessantly interrupted. The said members may move quite slowly and they preferably consist of rotatable knots or projections projecting in through the wall of the supply channel or hopper about in level with the upper edge 50 of the pressing piston or somewhat above the same.

Some constructional forms of the invention are illustrated in the accompanying drawing, in which Figure 1 is a vertical section through a grinding apparatus constructed in accordance with the invention.

Fig. 2 is a similar section of the lower part of the apparatus drawn to a larger scale and from which the mode of operation will be clearly understood. Figs. 3 and 4 indicate modified constructions.

The wooden blocks are pressed against the grinding stone 1 by means of the pressing pistons 2 in ordinary manner. From the block magazine 3 the blocks fall through the supply channels or hoppers 4 down into the grinding compartments proper between the stone 1 and the pistons 2. The dressing device for the stone 1 is arranged at 5.

Upon a shaft 6 two knot or cam disks 7 are arranged a suitable distance apart so that they may act upon the wooden blocks near their two ends. The drawing shows only one of these disks. The shaft 6 rotates slowly in the direction of the arrow 8, whereby the cam projections 7 will enter the channel through slots in the channel wall 9, then catch the nearest located block and move the blocks slowly upward, whereupon the projections will be withdrawn again through the wall slots. The block row 10, Fig. 2, consequently will be moved slowly upward and thereby constantly interrupt any bridge arches 11, 12 or 13 that might have been formed, so that the blocks may always fall freely down into the compartment in front of the pressing plates 2.

Instead of a shaft 6 with cam disks 7 endless chains with teeth or knobs may be arranged as shown in Fig. 3, or two screws 90 with a large thread pitch may be used as indicated in Fig. 4, or other members may be made use of which act so as to move slowly but safely the wooden blocks 10 upward and thereby to interrupt the bridge arches formed.

In order to counteract the unfavorable fact which does not seldom occur, namely that the blocks which are not reached by the cams 7 form bridge arches 12 from the pressing plate 2 to the lower part of the inner magazine or channel wall 20 or to another stationary point in the magazine, a ruler or list 14 is arranged above the stone 1 in such a manner that it is pressed backward under constantly increased pressure from the spring 15.

The list 14 is moved in guides 21 arranged concentrically to the stone 1. It is provided with two racks 16 engaged by gear segments 17 upon a shaft 18 having an arm 19 which presses against one end of a spring

15, the other end of which is in engagement with the magazine wall 20.

If therefore against this list 14 a bridge arch 12 is formed which is located in front 5 of the sharpening device casing 5, the list 14 will be pressed back in a curved path determined by the guides until the arch is broken.

A bridge arch 13 which may be formed 10 from the pressing plate 2 to the magazine wall 20 cannot bar the pressure because it is too much inclined in relation to the pressing direction.

The list 14 is, as mentioned, arranged 15 movably in such a manner that it travels in a path concentrically to the stone periphery. In the drawing this is obtained by attaching the list 14 to one or two sliding pieces 22 carrying the racks 16. The list 14 20 thereby will perform a pulsating buffer motion, what is necessary if the cam disks 7 shall be able to fulfil their purpose in a satisfactory manner.

It is obvious that the cam disks 7 or 25 equivalent raising members may be arranged at the wall 20 instead of being placed at the wall 9, or such member may be arranged at both walls. In the latter case the raising members at the wall 9 should 30 move upward with a speed which is different from that of the members arranged at the wall 20.

Claims:

1. In magazine grinding apparatuses for 35 the manufacture of wood pulp, the combination of a magazine compartment for wooden blocks to be ground, a grinding stone, pressing members for forcing said blocks against said stone, and movable members arranged at or in the wall of the magazine or the part of same conducting the blocks to the space between the stone and the pressing members in such a manner as to move the blocks located near the said 45 wall part in a direction away from the said space, whereby any self-carrying bridge-arches of blocks are incessantly interrupted.

2. In magazine grinding apparatuses for 50 the manufacture of wood pulp, the combination of a magazine compartment for wooden blocks to be ground, a grinding stone, pressing members for forcing said blocks against said stone, and slowly rotating cam disks arranged in the wall of the magazine or the 55 part of same conducting the blocks to the space between the stone and the pressing members, the rotating direction of the disks being so that their projections act to move the blocks located near the said wall part in 60 a direction away from the said space, whereby any self-carrying bridge-arches of blocks are incessantly interrupted.

3. In magazine grinding apparatuses for 65 the manufacture of wood pulp, the combination of a magazine compartment for wooden

blocks to be ground, a grinding stone, pressing members for forcing said blocks against said stone, and slowly rotating cam disks arranged just above the said pressing members and having projections entering 70 through slots in the lower part of the magazine space conducting the blocks down into the space between the stone and the pressing members, said projections having such a rotating direction as to move the blocks located near the wall of the said magazine part slowly upward, whereby any self-carrying bridge-arches of blocks are incessantly interrupted.

4. In magazine grinding apparatuses for 80 the manufacture of wood pulp as claimed in claim 1, the arrangement of upwardly movable bridge-arch interrupting members at the lower part of the outer wall of the channel conducting the blocks to the space 85 between the stone and the pressing member.

5. In magazine grinding apparatuses for 90 the manufacture of wood pulp, the combination of a magazine compartment for wooden blocks to be ground, a grinding stone, pressing members for forcing said blocks against said stone, upwardly movable members arranged in the wall of the magazine part 95 conducting the blocks to the space between the stone and the pressing members, and a spring-pressed list arranged at the upper part of the stone so as to be able to yield backward under influence of pressures from block-bridges formed between the said list and the pressing member, the upwardly 100 movable members acting to move the blocks located near the said wall part in a direction away from the said space, whereby any self-carrying bridge-arches of blocks are incessantly interrupted.

6. In magazine grinding apparatuses for 105 the manufacture of wood pulp, the combination of a magazine compartment for wooden blocks to be ground, a grinding stone, pressing members for forcing said blocks against said stone, upwardly movable members arranged in the wall of the magazine part 110 conducting the blocks to the space between the stone and the pressing members, a spring-pressed list arranged at the upper part of 115 the stone, and guides arranged concentrically with the stone axis so as to enable the list to yield backward under influence of pressures from block-bridges formed between the said list and the pressing members, the upwardly 120 movable members acting to move the blocks located near the said wall part in a direction away from the said space, whereby any self-carrying bridge-arches of blocks are incessantly interrupted.

7. In magazine grinding apparatuses for 125 the manufacture of wood pulp, the combination of a magazine compartment for wooden blocks to be ground, a grinding stone, pressing members for forcing said blocks against 130

said stone, upwardly movable members arranged in the wall of the magazine part conducting the blocks to the space between the stone and the pressing members, a spring-
5 pressed list arranged at the upper part of the stone, guides arranged concentrically with the stone axis, and a spring-pressed lever transmitting spring-pressure to the list so as to enable it to yield backward with an
10 increasing resistance under influence of pressures from block-bridges formed between the said list and the pressing member, the

upwardly movable members acting to move the blocks located near the said wall part in a direction away from the said space, where-
15 by any self-carrying bridge-arches of blocks are incessantly interrupted.

In testimony that I claim the foregoing as my invention, I have signed my name in presence of two subscribing witnesses.

PEDER CHRISTIAN SCHAANNING.
